PRODUCING APPARATUS FOR OIL WELLS

Chester A. Rasmussen, Long Beach, Calif., assignor to Rasmussen Service Company, Long Beach, Calif., a corporation of California

Application May 16, 1938, Serial No. 208,106

21 Claims. (Cl. 166—2)

My invention relates to the art of operating oil wells and with particular reference to an improved form of adjustable subterranean tubing valve.

Subterranean valves controlling flow into oil well tubing may be employed for various purposes. In one situation where the well taps a high pressure formation, a tubing valve may be employed with certain advantages to control the well stream and the pressure thereof at the level of the producing formation in contradistinction to the usual arrangement for controlling the well stream solely at the top of the well. In another situation a relatively deep formation tapped by a well supplies oil at such low pressure that there is relatively little tendency for the fluid to flow from that formation to the surface of the well, while a formation at a higher level in the same well supplies gas, or oil highly charged with gas, at a pressure far in excess of the requirements for free flow to the surface. In this latter situation a tubing valve may be employed to provide controllable means for utilizing pressure from the high pressure formation to promote flow from the low pressure formation at the lower level. As taught by my disclosure, in this latter situation a second tubing valve may be employed to control flow into the tubing from the lower of the two formations.

The general object of my invention is to provide a subterranean valve that may be adjusted at the ground level without the necessity of pulling the well tubing. It has heretofore been proposed in the art to arrange such a tubing valve to be adjusted by movement of an upper section of a tubing string relative to a fixed section of the tubing string extending below the valve. I have found that the inherent unavoidable disadvantages of such an arrangement include, among other things: the difficulty of arranging the well tubing for the required relative movement; the difficulty of ascertaining the effect of a given extent of tubing movement at the top of the well on the subterranean valve because of stretch in the tubing string; the difficulty of maintaining any given valve adjustment because of temperature changes in the tubing above the valve; the difficulties arising from friction opposing free movement of the adjustable portion of the tubing; and the difficulty of maintaining an effective seal around the movable portion of the tubing. These difficulties increase at an increasing rate with the depth of the well and in practice soon become insurmountable.

It is my object to avoid all the difficulties

mentioned above, and my invention is characterized by the concept that these difficulties may be avoided by adapting the tubing valve to be adjusted by means lowered into the tubing whenever adjustment is necessary. An important advantage of my new arrangement is that the tubing string may be mounted in the well as a solid column of pipe supported in a conventional manner with the valve incorporated at any desired level therein. Since the only difference between manipulating a weight at one depth and another is the difference in length of cable employed, my valve may be controlled with practically the same facility at any depth met in practice.

A more specific object of my invention is to provide an arrangement in which the valve means for controlling a tubing port is yieldingly held adjacent the tubing port and is adapted to be moved from one fluid-controlling position to another fluid-controlling position by a weight moving against the valve means and controlled from the surface of the well. In the preferred form of my invention, it is my object to provide means in the tubing string to limit the action of the valve-operating weight, and it is my further object to make the weight adjustable with respect to its engagement with such limiting means whereby the valve-operating weight may be preset at the surface of the well to open the valve to any predetermined extent.

In one form of my invention I have the object of providing yielding means such as a spring adapted to move the valve means upward after the valve means has been depressed by manipulation of a weight to a predetermined extent. In another form of my invention I provide a special tool to grapple a valve member to cause valve operation opposite from that produced by the weight. By employing a valve-operating means that is completely withdrawn from the well when not in use, I avoid the necessity of obstructing flow in the tubing to any degree whatsoever in the periods between valve-adjusting operations.

A further important object of my invention is to provide a subterranean tubing valve that may be renewed without pulling the tubing and to provide means for lowering a valve member into place in the tubing for such purpose.

A further object of my invention is to provide an arrangement in which two valves at widely separated levels in a tubing string may be separately adjusted or replaced without pulling the tubing string.

The above and other objects and advantages of my invention will be apparent from the detailed description to follow, taken with the accompanying drawings.

In the drawings:

Fig. 1 is a diagrammatic representation of an oil well incorporating one form of my invention;

Fig. 2 is an axial section through my valve assembly in the oil well tubing showing the valve in closed position;

Fig. 3 is a similar view showing the valve moved to an intermediate open position by the valve-operating weight;

Fig. 4 is a similar view showing the valve at full open position;

Fig. 5 is a similar view on a somewhat enlarged scale showing the inner sleeve depressed sufficiently to bring the automatic latch-releasing means into operation;

Fig. 6 is a transverse section taken as indicated by the broken line 6-6 of Fig. 2;

Fig. 7 is a slightly enlarged axial section of a second form of my invention incorporating a plurality of valve-controlled ports in the tubing string adapted to be opened successively by the inner sleeve;

Fig. 8 is an enlarged axial section of one of the valve-controlled ports of Fig. 7;

Fig. 9 is a fragmentary section taken as indicated by the line 9-9 of Fig. 8;

Fig. 10 is a transverse section taken as indicated by the line 10-10 of Fig. 7;

Fig. 11 is a vertical section through a well casing showing one form of my invention for controlling flow into the lower end of a string of tubing;

Fig. 12 is an axial section through the tubing and valve of Fig. 11, showing a valve-operating tool engaged therewith;

Fig. 13 is a side elevation partly broken away of the valve-operating tool shown in Fig. 12;

Fig. 13a is a transverse section taken as indicated by the line 13a-13a of Fig. 13;

Fig. 14 is a fragmentary longitudinal section similar to Fig. 12 indicating an alternate and reversed construction;

Fig. 15 is a diagrammatic representation of an oil well in which the tubing string incorporates two of my valves at widely separated levels;

Fig. 16 is an axial section through the tubing string of Fig. 15 showing a valve-controlling tool engaging the lower of the two valves;

Fig. 16a is a transverse section taken as indicated by the line 16a-16a of Fig. 16;

Fig. 16b is a transverse section taken as indicated by the line 16b-16b of Fig. 16;

Fig. 17 is an axial section through a fragment of a tubing string showing an arrangement by virtue of which the valve member may be completely withdrawn for replacement;

Fig. 18 is a fragmentary section similar to Fig. 12 showing a grappling tool being moved into engagement with a valve member; and

Fig. 19 is an axial section through a portion of a tubing string showing a device for lowering a valve member into place in the tubing.

Fig. 1 represents a typical situation in which a perforated oil well casing 20 extends downward through three spaced oil sand formations 21, 22, and 23 separated by impervious formations 24 and 25, and in which the lowermost producing formation 23 is at relatively low pressure inadequate to force oil from the well, while either or both the upper producing formations

21 and 22 produce gas or oil at pressures exceeding the requirements of free flow.

A string of tubing, generally designated 26, for bringing oil to the surface of the well is inserted in the casing 20, the tubing terminating in a perforated portion 27 submerged in the oil 28 in the casing from the low pressure formation 23. In the practice of my invention, I contemplate providing a packer 29 of conventional type 10 that forms a seal between the tubing and the casing at the impervious formation 25, thereby dividing the annular space between the tubing and casing into a low pressure zone 32 below the packer in communication with the low pressure formation 23 and a high pressure zone 33 above the packer in communication with the high pressure formations; and I further contemplate incorporating in the string of tubing 26 within the high pressure zone 33 my tubular valve assembly generally designated 34.

The valve assembly, as viewed in side elevation in Fig. 1, comprises an upper coupling 35, an outer valve sleeve 36, and a lower coupling 37, these three members being rigidly threaded together and rigidly incorporated in the tubing string as an integral portion thereof. The outer valve sleeve has one or more longitudinally disposed valve ports 38, preferably in the form of longitudinal slots, and slidably mounted within 30 the outer sleeve is a valve means, such as an inner valve-sleeve 39, movable downward to uncover the valve port 38 thereby to provide communication between the annular high pressure zone 33 and the interior of the string of tubing. 35 The movable or inner valve-sleeve 39 is yieldingly supported and urged toward its upper valve-closing position by suitable means such as a helical spring 40 that is seated in the lower coupling 37. The lower end of the spring may rest, for example, on a bushing 42 mounted in the coupling and may embrace a tubular guide 43 resting on the bushing 42.

The latch means for retaining the inner valve-sleeve 39 at selected open positions of the valve 45 in opposition to pressure from the spring 40 may be a detent mechanism comprising a member on the outer valve-sleeve adapted for engagement with a cooperating member on the inner valve-sleeve. The latch or detent means carried by 50 the inner valve-sleeve 39 may comprise a relatively extensive flexible pawl 45 disposed in a longitudinal slot 46 in the wall of the inner valve-sleeve, the pawl being secured by a pair of screws 47 that extend through the wall of the 55 inner valve-sleeve into a tubular reinforcement 48 at the bottom end of the valve-sleeve.

This pawl is designed normally to press outward against cooperative ratchet means fixed to the outer valve-sleeve 36. To provide such 60 ratchet means, I prefer to counterbore the outer valve-sleeve 36 to provide a seat for a ratchet cylinder 49 slidingly embracing the inner valve-sleeve 39, the ratchet cylinder being supported by the inner end of the lower coupling 37 of the valve assembly. Preferably, I provide three pawls 45 spaced circumferentially to cooperate with three corresponding series of ratchet teeth 52 in the ratchet cylinder 49 (Fig. 6). To prevent 65 relative rotation between the cooperating members, suitable means may be provided, such as a setscrew 53, in the inner valve-sleeve 39 extending radially outward into sliding engagement with a complementary longitudinally disposed slot 54 in the ratchet cylinder 49.

At the closed position of the valve, the pawls

45 press outward against a smooth upper portion 55 of the ratchet cylinder, as indicated by Fig. 2. If the inner valve-sleeve 39 is depressed to any intermediate position, permitting flow through the valve ports 38, the pawls 45 automatically engage teeth in the ratchet cylinder, as indicated in Fig. 3, to hold the valve open.

To open the valve, it is merely necessary to provide means for moving the inner valve-sleeve downward against the action of the spring 40. For example, as indicated in the drawings, such valve-operating means may comprise an elongated weight 57 that is lowered into the tubing string by means of a suitable cable 58, the weight having a head 59 at its lower end for abutment against the upper end of the inner valve-sleeve 39. The weight 57 may be of such mass that it is necessary merely to lower the weight against the upper end of the movable valve-sleeve, as indicated in Fig. 2, to cause the valve-sleeve to 20 gravitate downward as required, or a lighter weight may be used to depress the valve-sleeve by impact rather than sheer weight.

Preferably, the weight is adjustable at the surface of the well to open the tubing valve to a predetermined extent. To provide for such action, the upper coupling 35 of the valve assembly may be formed with an inwardly disposed stop means such as a tapered annular shoulder 60, and the periphery of the weight 57 may be threaded to receive a complementary adjustable stop-collar 62, the adjustment of the collar on the weight determining the extent to which the movable valve-sleeve is depressed by the weight. It will be noted that the weight is formed with an axial passage 63 and radial apertures 64 providing a fluid course to facilitate movement through the oil column in the tubing string.

A further refinement is the provision of means to close the valve from an open position without the necessity of removing the valve assembly from the well, this function being provided in the instant form of my invention by automatic release means to render the valve latch ineffective. When the movable valve-sleeve is depressed to an extreme position, the release means holding the latch means ineffective until the movable valve-sleeve 39 is raised by the spring 40 to the closed position of the valve.

In the arrangement suggested by the drawings, longitudinal slots 65 in the ratchet cylinder 49 divides each of the ratchet teeth 52 into two laterally spaced portions designated 52a in Fig. 6. Each of the longitudinal slots 65 is widened at the periphery of the ratchet cylinder to provide a channel designated 66 to retain and guide a complementary release slide 67. Each release slide 67, as best shown in Fig. 5, has an integral longitudinal rib 68 extending into the inner narrower portion of the longitudinal slot 65. The rib has a relatively shallow portion 69 toward its upper end, an inclined cam portion 70, and an elevated portion 72 toward its lower end having a shallow recess 73. The release slides 67 are relatively short in comparison with the slots 65, and are freely slideable in the slots so that normally the release members rest at the lower ends of the slots as indicated in Figs. 2 and 3.

If the tubing valve is to be closed, the stop-collar 62 is adjusted at an elevated position somewhat higher than shown in Fig. 4, so that when the weight 57 is lowered against the movable valve-sleeve 39, the valve sleeve is depressed to the extent indicated in Fig. 5. This movement forces the pawls 45 up the cam portions 70 of the

5 release slides 67 and into the depressions 73 of the slides, at which positions the pawls are out of range of the ratchet teeth 52. When the weight 57 is removed from the well after depressing the inner valve-sleeve 39 to the extent described, the spring 40 moves the inner valve-sleeve upward bringing the pawls 45 into engagement with the shoulders 74 at the upper ends of the shallow recesses 73, with the result that the slides are carried upward with the moving valve-sleeve. When the release slides are stopped by the upper ends of the slots 65, the pawls continuing upward with the inner valve-sleeve escape from engagement with the shoulders 74 and then move outward against the smooth portion 55 of the ratchet cylinder above the ratchet teeth at the closed position of the valve shown in Fig. 2. The release slides then gravitate to their normal positions at the lower ends of the slots 65.

Another form of my invention shown in Figs. 7 to 10 is similar in construction to the first form of my invention, corresponding prime numbers indicating corresponding parts. Instead of employing longitudinal valve ports in the outer valve-sleeve 36', I provide a plurality of spaced valves arranged to be opened by depression of the inner valve-sleeve 39', the first two of the plurality of valves being shown in Fig. 7.

Each of the valves includes a valve member 38 that has a ribbed stem 79 and is adapted to seat in a suitable hardened bushing 80, the valve member being normally held in its closed position by a valve spring 81 acting between the bushing and an annular stop 82 on the valve stem. The valve stem 79 of each of the valves extends into a cooperative cam slot 83 cut longitudinally of the periphery of the inner valve-sleeve 39'. To prevent relative rotation of the inner valve-sleeve, suitable means may be provided, such as a setscrew 84, in the inner valve-sleeve in sliding engagement with a longitudinal guide slot 85 in the outer guide-sleeve. Each of the cam slots 83 is extended to the upper end of the inner valve-sleeve to provide a channel for passage of fluid from the high pressure zone 33 of the well into the interior of the tubing string. Preferably, the inclined surfaces 86 in the cam slots 83 are so disposed that the various valves will be opened in succession as the inner valve-sleeve is progressively depressed. Thus, it will be noted that in the arrangement shown in Fig. 7, the uppermost peripheral valve will be fully opened before progressive opening of the second valve will be initiated.

Under some circumstances it is desirable to have valve means at the lower end of a string of tubing to control flow of fluid into the tubing instead of limiting flow control to means at the top of the tubing string. Such an arrangement is advantageous, for example, when there is a high gas ratio in the fluid stream and the pressure is far in excess of the head necessary to force the fluid column to the surface. In such a situation I have found that waste of gas is materially reduced if the fluid stream is throttled down by a subterranean valve so that the pressure of the column of fluid in the tubing string does not greatly exceed the pressure required for unassisted flow. It is apparent also that such an arrangement gives two control points for the well flow, one control point being at the bottom of the tubing and the other control point being at the surface.

Fig. 11 shows a string of tubing 90 in a perforated well casing 91, the tubing being sealed

at the bottom by a suitable plug 92 and having near its lower end one or more peripheral ports 93 controlled by one of my valve arrangements, for example, the valve arrangement shown in Fig. 12, one of the preferred forms of my invention.

In Fig. 12 the outer valve-sleeve 94 is connected to the tubing 90 by a coupling 95, the outer valve-sleeve serving as an integral part of the tubing string. For a purpose that will be explained later, the coupling 95 may have an inwardly extending annular shoulder 96 of lesser internal diameter than the outside diameter of a valve-sleeve 97 that is slidably telescoped in the outer valve-sleeve 94. The outer valve-sleeve 94 is apertured to provide the ports 93 and, preferably, has an internal annular channel 98 communicating with these various ports.

The plug 92 which may be solid, as shown, or may be formed simply by flattening and welding one end of a short nipple, is threaded into a collar 99 that is in turn threaded into the lower end of the outer valve-sleeve 94.

The sliding inner valve-sleeve 97 is provided with a plurality of peripheral ports 100, which may be graduated in size, as indicated by the drawings. For the purpose of releasably retaining the inner valve-sleeve at various positions to control flow through the ports 93, the inner valve-sleeve may be formed with a plurality of annular grooves 102 in its periphery for yielding engagement by a circular series of paws or latch members 103. In the construction shown, these flexible latch members are integral with a flanged ring 104 that is retained between the upper end of the collar 99 and an internal annular shoulder 105 integral with the outer valve-sleeve 94. To provide room for radial flexure of these latch members, the outer valve-sleeve is cut away to provide an annular space 106.

It is contemplated that the inner valve-sleeve and the paws will be so constructed and arranged that the inner valve-sleeve will be adequately supported to maintain any adjustment but may be shifted longitudinally by a suitable means lowered into the tubing string. Thus, the inner valve sleeve 97 may be readily shifted downwardly, as required, by employing the elongated weight or valve-operating means 57 in the manner previously described.

Since, in this form of my invention, I do not provide a spring for moving the inner valve-sleeve upward, I may arrange for the valve-sleeve to be engaged and moved upward by a suitable grappling tool. For example, I may cut an internal annular channel 109 in the sliding valve-sleeve to be engaged by a grappling tool generally designated 110 in Figs. 12, 13, and 18.

As best shown in Fig. 13, the body 111 of the grappling tool is of tubular construction, being open at its lower end and having a series of radial apertures 112 so that fluid may pass through the tool when it is being lowered through the fluid column in the tubing string. The upper end of the body 111 may be screw-threadedly connected to a jar that includes a rod 113 having an anvil head 114. A cylindrical hammer 115 surrounds the rod 113 with an inwardly extending annular shoulder 116 disposed to engage the anvil head 114 for supporting the tool body 111. This cylindrical hammer 115 is supported by means such as a cable or heavy piano wire (not shown), by means of which, after the tool is lowered into position, the hammer may be manipulated for repeated impact against

the anvil head 114 in a manner well understood in the art.

Towards its upper end the tool body is embraced by a collar 118 secured thereto as by a pin 119. Spaced below this fixed collar is a second sliding collar 120, the tool body being enlarged to provide a shoulder 121 against which this collar is normally urged by a helical spring 122 that embraces the tool body in compression between the two collars 118 and 120. Slidably embracing the tool body 111 below the sliding collar 120 is a grappling sleeve 125 having integral therewith a circular series of longitudinally extending flexible fingers 126, the lower ends of the fingers providing a circular series of enlargements 127. The grappling sleeve is formed with a shoulder 128 dimensioned to engage the upper end of the inner valve-sleeve 97, and the fingers 126 are dimensioned to place the enlargements 127 in registry with the engagement channel 109 as may be understood by reference to Fig. 12.

The grappling sleeve 125 is supported by a collar 130 that is fixed with respect to the tool body 111 by a suitable pin 131. In one practice of my invention, this pin is of frangible material and is severed to free the collar 130 in the course of adjusting the tubing valve, the collar being thereby permitted to drop against an annular shoulder 132 provided by an enlargement 133 in the tool body. To permit insertion of the pin 131, diametrically disposed apertures 134 are provided in the grappling sleeve 125, and to permit subsequent removal of the severed parts of the pin, the upper end of the grappling sleeve may be cut away at diametrically opposite points, as indicated at 135. When the pin 131 holds the collar 130 at its elevated position, the grappling sleeve 125 is at a position placing the finger enlargements 127 opposite a tapered circumferential rib 136 formed in the tool body 111, this rib serving to expand the circular series of finger enlargements into an outside diameter greater than the inside diameter of the sliding valve-sleeve 97 so that the finger enlargements may engage the engagement channel 109 of the valve-sleeve in a positive manner, as shown in Fig. 12.

If, in the course of operating a well, it is desirable to shift the inner valve-sleeve upward, the grappling tool 110 is lowered into the well, the tool being guided past all obstructions in the tubing string by a conical nose 137. When the grappling tool encounters the inner valve-sleeve 97, it is forced into the sleeve either by sheer weight of the tool or by impacts of the hammer arrangement described. Since the circular series of finger enlargements 127 is expanded by the rib 136 into greater external diameter than the internal diameter of the sliding valve-sleeve, the forcing of the tool body 111 into the valve-sleeve causes the finger enlargements to be dislodged upward, which dislodgment causes the grappling ring to move against the sliding collar 120 and to further compress the spring 122. The finger enlargements 127 are so dimensioned with respect to the diameter of the tool body that when they are dislodged from the periphery of the expanding rib 136, the fingers may enter the sliding valve-sleeve, as shown in Fig. 18. It is apparent that the spring 122 will continuously tend to restore the finger enlargements to their normal positions on the periphery of the expanding rib 136 so that as soon as the finger enlargements reach the engagement channel 109 of the valve-sleeve, the spring 122 causes relative movement between the grappling sleeve 125 and the tool body 111,

restoring the finger enlargements to their normal positions thereby bringing the grappling tool into positive engagement with the valve-sleeve, as indicated in Fig. 12.

Once the grappling tool is properly seated, the cable may be spooled in to withdraw the tool. The upward movement of the grappling tool carries the sliding valve-sleeve 97 to its uppermost position which may be the closed position of the valve, at which point the sliding valve-sleeve of Fig. 12 abuts the shoulder 96 whereupon jarring the tool severs the pin 131. Severance of the pin permits the grappling sleeve to drop, thereby shifting the finger enlargements 121 downward to a position of restricted outside diameter indicated in dotted lines in Fig. 13. This downward movement of the finger enlargements permits the grappling tool to retract in effective diameter to escape from the valve-sleeve.

It is apparent from the foregoing description that the annular shoulder 96 formed in the tubing string serves the dual purpose of a tool-stop to cooperate with the valve-operating tool 51 and of a stop for the valve-sleeve to cause disengagement of the grappling tool 110. In one practice of my invention, where it is desirable to arrange for replacement of the sliding valve sleeve without the necessity of pulling the tubing, this latter function of the shoulder 96 is omitted, the shoulder being of sufficiently large internal diameter, as indicated at 96a in Fig. 17, to pass the sliding valve-sleeve 97a. The shoulder 96a, however, is smaller in internal diameter than the tubing 90 so that the valve-operating tool 51a shown in dotted lines may be employed to depress the sliding valve-sleeve to a predetermined extent, as previously described.

The purpose of Fig. 14 is to show that the valve construction of Fig. 12 may be modified, for example, by mounting latch members 103a on the sliding valve sleeve 97b instead of mounting the latch members on the outer sleeve 94b. In the construction shown, the lower end of the sliding valve-sleeve 97b is cut to form the latch members integral therewith. The latch members are adapted to engage internal annular grooves 102a in the outer sleeve member 94b to provide for the mode of operation previously described.

A feature of my invention, as previously noted, is that it permits the employment of two separately adjustable tubing valves disposed in a tubing string at widely separated levels. Fig. 15, for example, indicates an arrangement similar to that of Fig. 1 with the addition of a valve to control flow into the lower end of the tubing. This latter arrangement is noteworthy in that it affords complete control of fluid flow into the tubing instead of control of only one of the two fluid streams involved. Fig. 15 shows a string of tubing 150 in a perforated well casing 151, a packer 152 sealing off the annular space between the tubing and casing between two producing formations. An upper tubing valve generally designated 153 at the upper producing formation controls flow into the tubing through one or more tubing ports 154, and at the lower end of the tubing closed by a plug 155 a lower tubing valve 156 controls flow into the tubing through one or more ports 157. The manner in which the lower valve 156 may be incorporated in the tubing string to be adjusted independently of the upper valve 153 may be understood by reference to Fig. 16.

Fig. 16 shows the lower parts of the upper tubing valve 153, including an outer valve-sleeve 75

160 forming an integral part of the tubing string, an inner valve-sleeve 161 slidably mounted therein, and latch members 162 cooperating with peripheral grooves 163 in the inner valve-sleeve. The outer valve-sleeve 160 is connected to the tubing 150 below the valve by a suitable connecting collar 164.

The lower tubing valve 156 is similar in construction to the upper valve 153, the construction being substantially that previously described with reference to Fig. 12. Thus, the lower valve 156 includes an outer valve-sleeve 166 that may be identical in construction and dimension to the outer valve-sleeve 160 of the upper valve. The outer valve-sleeve 166 is connected to the tubing 150 by a collar 167 having the same internal clearance as the outer valve-sleeve and is closed at the bottom by the plug 155 that is connected thereto by a collar 168. The sliding valve-sleeve 170 of the lower tubing valve may have the same outside diameter as the sliding valve-sleeve 161. As shown in the drawings, the sliding valve-sleeve 170 has a series of longitudinally spaced ports 171 intended to be moved successively into registration with an annular channel 172 formed in the inner wall of the valve-sleeve 166 in communication with the tubing ports 151. The sliding valve-sleeve 170 has an inner engagement channel 173 to cooperate with a grappling tool, as previously described, and has near its lower end a series of external annular grooves 174 adapted to be releasably engaged by a circular series of latch members 175 in the manner previously described.

The sliding valve-sleeve 161 of the upper tubing valve 153 is shifted downward as required by a weight or valve-operating tool 51, as previously described. The sliding valve-sleeve 161 may be free to be withdrawn completely from the tubing by virtue of an arrangement shown in Fig. 17. When it is necessary to shift the sliding valve-sleeve 161 upward, the grappling tool 110 is forced into engagement with the valve-sleeve in the manner previously described. It will be understood, of course, that the engagement of the latch members 162 with the sliding valve-sleeve is sufficient to cause the finger enlargements 136 of the grappling tool to be retracted without danger of the grappling tool forcing the valve-sleeve downward. Once the sliding valve-sleeve is positively engaged by the grappling tool, it is drawn to the surface of the well and is subsequently lowered by means that will be later described into a position to start a new valve-operating cycle.

When the upper sliding valve-sleeve 161 is removed from the well, the grappling tool may be lowered to engage the lower sliding valve-sleeve 170 so that the lower valve-sleeve may be drawn to the surface of the well for the same purpose.

While the upper sliding valve-sleeve 161 may readily be depressed to a predetermined and adjustable extent, it is apparent that in the absence of an annular shoulder or tool-stop 96a for the lower sliding valve-sleeve 170, some special type of valve-operating tool is desirable for predetermined adjustment of the lower valve. Such a valve-operating tool is generally designated 178 in Fig. 16. The valve-operating tool 178 has a tubular body 179 threaded to be embraced in an adjustable manner by a stop-collar 180, the tool body being dimensioned to move freely into the sliding valve-sleeve 170 and the stop-collar 180 being dimensioned to engage the upper end of the valve-sleeve, as shown in Fig. 16. The tool

body 179 may be connected with a cable or heavy piano wire 181 through a jar generally designated 182.

The tool-stop to cooperate with this particular valve-operating tool may comprise a bar 183 seated in longitudinal slots 184 in the connecting collar 168, the bar being disposed diametrically across the interior of the tubing string in the path of the valve-operating tool. When the valve-operating tool 178 is lowered into engagement with the sliding valve-sleeve 170 and is jarred downward until the leading end of the valve-operating tool strikes the bar 183, the valve-sleeve will be depressed to an extent determined in advance by the setting of the stop-collar 180 on the tool body 179. The lower sliding valve-sleeve 170 is of smaller inside diameter than the upper sliding valve-sleeve 161 so that a stop-collar 180 may be dimensioned as shown in Fig. 16 to pass through the upper sliding valve-sleeve, in which case the lower valve-sleeve may be depressed in a controlled manner from the surface of the well without the necessity of removing the upper sliding valve-sleeve 161 in advance. The stop-collar 180, however, may if desired be of substantially larger diameter to serve as a guide for centering the tool body 179 as the tool approaches the lower sliding valve-sleeve. In the latter case, of course, the upper sliding valve-sleeve 161 must be pulled from the tubing in advance of such adjustment of the lower valve.

Any number of expedients may be resorted to for lowering the upper sliding valve-sleeve 161 into position in the well. For example, the valve-sleeve may be lowered into the well in engagement with the grappling tool 110, the pin 131 being strong enough to carry the weight of the valve-sleeve but being frangible enough to be sheered when the tool is pulled upward with the valve-sleeve engaged by the latch means 162. For example, soft wire may serve the purpose of the pin 131. It is contemplated that the frangible pin will hold the valve-sleeve against the shoulder 128 of the grappling tool so that any impact of the lower end of the valve-sleeve against projections in the tubing string during the descent of the valve-sleeve will be resisted by the shoulder 128 of the grappling tool instead of being exerted in sheer across the frangible pin. With ordinary care, the valve-sleeve may be brought to rest against the latch members 162 and then jarred into engagement with the latch members, the latch members seating in the lowermost of the grooves 163.

In an alternative procedure, the upper sliding valve-sleeve 161 may be lowered into its place by a tool constructed as indicated in Fig. 19. This tool generally designated by numeral 190 has a body 191 dimensioned to be inserted in the valve-sleeve 161, the body having an annular shoulder 192 to seat against the upper end of the valve-sleeve. A piece of soft wire 193, or other frangible element, passes through a diametrical bore in the body 191 and through diametrically opposite valve ports 195 in the sliding valve-sleeve 161, the disposition of the bore 194 being such that the wire holds the valve-sleeve against the annular shoulder 192. Above the shoulder 192 the body 191 of the tool is provided with threads to adjustably receive a stop-collar 196, the stop-collar being dimensioned to engage the shoulder 62a in the same manner as the stop-collar 62a shown in broken lines in Fig. 17. This tool is lowered on a cable and preferably is pro-

vided with a jar connection in a manner previously described. The advantage of using this tool instead of the grappling tool for lowering the valve-sleeve into the tubing is that the stop-collar 196 may be set to cause the valve-sleeve to be forced downward any desired extent to seat the latch members 162 in a selected peripheral groove 163.

As for the lower sliding valve-sleeve 170, it may be lowered from the surface of the well by the valve-operating tool 178 if that tool is provided with a diametrical bore 197 to receive a wire 198, or other frangible element, passing into valve ports 171a, as indicated in Fig. 16. It is apparent that the collar 180 may be set to move the sliding valve-sleeve 170 to any pre-selected disposition. A number of bores 197 may be provided in the tool body so that the desired releasable connection with the valve-sleeve may be had for any adjustment of the stop-collar 180.

Since any of the valve-operating tools described may be carried by a piano wire, I may pass the piano wire through a packing gland at the top of the well and proceed with lowering and manipulating the tool without leaving the well open.

The tool may be entirely withdrawn from the tubing during the intervals between valve-adjusting operations, but, by virtue of the tubular character of my tool, it may be left suspended in the tubing without material interference with fluid flow if desired.

While I prefer to lower the tools on wires or cables and to depend upon jars for operation of the tools, as heretofore described, in one practice of my invention I may simply drop a tool with no cable into the tubing to operate a valve-sleeve by impact, and then later fish out the tool.

At the lower end of the tubing, sand may eventually enlarge the ports 157 in the outer valve-sleeve and the various ports 171 in the inner valve-sleeve. Enlargement of the ports 157 is no serious disadvantage, however, so long as the inner valve-sleeve 170 may be replaced, as required.

I have shown and described preferred embodiments of my invention in specific detail for the purpose of disclosure, and to illustrate the principles involved. It will be apparent to those skilled in the art that various changes and modifications may be made without departing from the spirit of my invention, and I reserve the right to all such changes and modifications that properly come within the scope of my appended claims.

I claim as my invention:

1. The combination with a well tubing having a subterranean intake port of a valve mechanism controlling flow through said port, said mechanism including: a member movable in the tubing; yielding means in the tubing to urge said movable member in one direction; latch means to hold said movable member in opposition to said yielding means; and valve-operating means adapted to be lowered into the well and to move said movable member from one latched position to another in opposition to said yielding means.

2. The combination with a well tubing of: a cylindrical member comprising a portion of the tubing, said member having an intake port, and an annular channel in its inner wall communicating with said port; a cylindrical valve-sleeve movably telescoped in said cylindrical member, said valve-sleeve having a series of longitudinal

spaced ports and being adapted to be moved to bring said ports successively into registration with said channel; means to hold yieldingly said valve-sleeve at selected positions in said cylindrical member; and means adapted to be lowered into the well to force said valve-sleeve from one position to another.

3. The combination with a well tubing having a subterranean intake port of a valve mechanism controlling flow through said port, said mechanism including: a member movable up and down in the tubing, said member being adapted to be moved downward by an object lowered into the tubing thereby to move said mechanism in one direction; yielding means in the tubing urging said movable member upward, thereby tending to move the valve mechanism in the opposite direction; latch means to prevent movement of said member by said yielding means; and means adapted when said movable member is lowered to a predetermined position to render said latch means inoperative until said yielding means returns the movable member to an upper position.

4. The combination with a well tubing having a subterranean intake port of: a valve mechanism controlling flow through said port; a member included in said mechanism and adapted to be moved up and down in the tubing to actuate said mechanism; a stop in the tubing to limit the upward movement of said movable member; a grappling tool adapted to be lowered into the tubing and to engage and lift said movable member; and frangible means incorporated in said grappling tool to hold the tool in grappling disposition, said frangible means being adapted to break and permit the grappling tool to take an ineffective disposition when said movable member is drawn upward against said stop.

5. The combination with a well tubing having a subterranean intake port of: valve means adapted to be lowered into the tubing to control flow through said port; means in the tubing to yieldingly retain said valve means in the vicinity of said port; means to lower said valve means into the tubing into engagement with said yielding means, said lowering means being adapted to abut said valve means in a positive manner to prevent upward movement of the valve means relative to the lowering means; and frangible means interconnecting said lowering means and valve means with the lowering means abutting the valve means, said frangible means being adapted to break and thereby release the valve means when the lowering means is lifted after the valve means is engaged by said yielding means.

6. In an oil well having a casing receiving fluid from a plurality of vertically spaced producing formations, the combination with said casing of: a string of tubing in the casing extending through one of said formations to a lower of said formations; means forming a seal between said casing and tubing string intermediate said two formations; valve means in said tubing above said seal to admit fluid into the tubing from the upper of said two formations; and valve means in said tubing below said seal to admit fluid into the tubing from the lower of said two formations, each of said valve means being adapted to be operated by an object lowered into the tubing.

7. The combination with a well tubing for conveying fluid to the top of a well of: a subterranean valve movable through a series of open

positions for permitting flow into the tubing at various rates, said valve being adapted to maintain any one of said open positions to which it may be moved; and a valve-operating tool separate from and independent of the valve for insertion into said well tubing at the top of the well after said tubing and valve are installed in the well, said tool being adapted for lowering through the tubing against said valve to move said valve from one of its open positions to another.

8. The combination with a well tubing of: a subterranean valve movable through a series of open positions for permitting flow into the tubing at various rates, said valve being adapted to maintain any one of said open positions to which it may be moved; a valve-operating tool for lowering into the tubing against said valve to move said valve from one of its open positions to another; and a stop in the tubing to limit movement of said tool against said valve.

9. The combination with a well tubing of: a subterranean valve movable through a series of open positions for permitting flow into the tubing at various rates, said valve being adapted to maintain any one of said open positions to which it may be moved; a stop in said tubing; and a tool adapted to be lowered into said tubing to move said valve from one of its positions to another, said tool being adjustable with respect to the spacing of its points of contact with said stop and valve, whereby the tool may be set at the surface of the well to cause a predetermined valve movement in the well.

10. The combination with a well tubing of: a subterranean valve movable through a series of open positions for permitting flow into the tubing at various rates; means in the tubing normally serving to yieldingly restrain movement of said valve, said means being effective for this purpose at any one of a number of open positions for the valve; and a valve-operating tool for lowering into the tubing against said valve to move said valve from one of its open positions to another in opposition to said restraining means.

11. The combination with a well tubing of: a subterranean valve movable through a series of open positions for permitting flow into the tubing at various rates; means in the tubing normally serving to yieldingly restrain movement of said valve, said means being effective for this purpose at any one of a number of open positions for the valve; a stop in said tubing; and a tool adapted to be lowered into said tubing to move said valve from one of its positions to another in opposition to said restraining means, said tool being adjustable with respect to the spacing of its points of contact with said stop and valve, whereby the tool may be set at the surface of the well to cause a predetermined valve movement in the well.

12. The combination with a well tubing having at least one subterranean port of: a subterranean valve means controlling fluid flow through said port; a yielding latch adapted to engage said valve means at selected open positions of the valve that permit different rates of fluid flow; and a means adapted to be lowered into said tubing to shift said valve means from one of said latched positions to another.

13. The combination with a well tubing having at least one subterranean peripheral intake port of: a valve member slidably mounted in the

tubing for movement to control fluid ingress through said port; means in the tubing to yieldingly hold said valve member set at various open positions permitting various rates of flow through said port; and means adapted to be lowered into the tubing to move said valve member from one of its set positions to another set position.

14. The combination with a well tubing of: a subterranean valve movable up and down through a series of open positions for permitting various rates of fluid flow into the tubing, said valve being adapted to maintain any one of said open positions to which it may be set, said valve being adapted to be moved downward by a weight lowered into the tubing and to be moved upward by a grappling tool.

15. In a well, the combination of: a tubing; valve means to control flow of well fluids into said tubing; a movable member included in said valve means and adapted to be moved up and down to adjust the valve for various rates of flow into the tubing, said member being adapted to be moved downward by a means lowered into the tubing and to be moved upward by a grappling tool; and means to hold the valve set at whatever position to which it may be adjusted.

16. The combination with a well tubing of: a valve member adjustably controlling fluid flow in the tubing; a depressing tool adapted to be lowered into the tubing to depress the valve member for adjustment in one direction; and a grappling tool adapted to be lowered into the tubing to engage and lift the valve member for adjustment in the opposite direction.

17. A combination as set forth in claim 16 in which a stop is provided in the tubing to limit downward movement of said depressing member, and in which said depressing member is adjustable with respect to its points of contact with said stop and said valve member.

18. The combination with a well tubing of: a removable valve member for the tubing; means to releasably support the valve member in the tubing in a manner to retain the valve member at set positions but to permit movement of the valve member from one set position to another for adjustment of flow in the tubing; a stop in the tubing; and releasable means to lower the

valve member into the well to a predetermined set position, said means being adapted to engage said stop when the valve member reaches said predetermined position.

19. A combination as set forth in claim 18 in which frangible means is incorporated in the connection between said lowering means and the valve member, said frangible means having insufficient strength to withstand the resistance of said valve supporting means to upward movement of the valve member.

20. The combination with a well tubing for conveying fluid to the top of a well of: a valve member dimensioned and adapted for insertion into the tubing at the top of the well for movement through the tubing from the well surface to a plurality of operative subterranean positions selectively, which positions differ in rates of fluid flow permitted by said valve member; a tool adapted to releasably engage said valve member externally of the well and to lower said valve member through said tubing to the region of said subterranean positions; and a stop in the well to limit the lowering movement of said tool and thereby to limit the lowering movement of said valve member to a predetermined one of said subterranean positions.

21. The combination with a well tubing for conveying fluid to the top of a well of: a subterranean valve movable through a series of open positions for permitting flow into the tubing at various rates, said valve being adapted to maintain any one of said open positions to which it may be moved; a valve-operating weight dimen-

30 sioned for insertion into said tubing at the top of the well and adapted for lowering into the tubing against said valve; a flexible member attached to said weight for lowering the weight into the tubing from the top of the well and for manipulation from the top of the well to cause said weight to move said valve from one of its open positions to another by repeated impact against the valve; and a stop in the tubing to limit the movement of said tool against said valve at a predetermined point to place said valve at a predetermined one of said open positions.

CHESTER A. RASMUSSEN.
